UNITED STATES PATENT OFFICE.

JOHN POLESKI AND JOSEPH TUVCAK, OF ST. CATHARINES, ONTARIO, CANADA.

DESIGN FOR A FLY CATCHER.

Application filed April 26, 1922. Serial No. 1,976. Term of patent 14 years.

To all whom it may concern:

Be it known that we, JOHN POLESKI and JOSEPH TUVCAK, citizens of Canada and Poland, respectively, residing at St. Catharines, in the Province of Ontario and Dominion of Canada, respectively, have invented a new, original, and ornamental Design for Fly Catchers, of which the following is a specification, reference being had to the accompanying drawings, forming a part hereof.

The figure is a perspective view showing our new design.

We claim:—

The ornamental design for a fly catcher as shown.

JOHN POLESKI.
JOSEPH TUVCAK.

In the presence of:—

W. MARGUERITE KANE,
ISABEL MACSPORRAN.
